UNITED STATES PATENT OFFICE.

LORENZ KONRAD BRAREN, OF MUNICH, GERMANY, ASSIGNOR TO THE FIRM FRIEDRICH DECKEL, FABRIK FÜR PRÄZISIONSMECHANIK UND MASCHINENBAU, OF MUNICH, GERMANY.

SPEED-CHANGING CAM-DRIVING MECHANISM.

Original application filed November 28, 1922, Serial No. 603,871. Divided and this application filed June 4, 1924. Serial No. 717,713.

To all whom it may concern:

Be it known that I, LORENZ KONRAD BRAREN, a citizen of Germany, residing at 22 Porten Strasse, Munich, Bavaria, Germany, have invented certain new and useful Improvements in Speed-Changing Cam-Driving Mechanisms, of which the following is a specification.

The present invention relates to cam driving mechanism for varying the speed and may for instance be used to advantage in connection with screw making and turning lathes. Such an application is shown and described in my copending application, filed

15 Nov. 28, 1922, Serial No. 603,871.

The object of my invention is to provide an improved mechanism for imparting alternately a slow and fast movement to a rotating member. When applied to a screw 20 machine one or several cams are mounted on an auxiliary cam shaft and this shaft is driven alternately by the main cam shaft rotating at a constant slow speed and by a fast rotating drive shaft, whereby the coupling 25 of the auxiliary cam shaft with both driving shafts is controlled in such a manner that the driven shaft completes each revolution in the same amount of time as is needed by the main cam shaft for one revolution.

In the drawings accompanying and forming part of this specification—

Figure 1 is a rear elevation of a screw making and turning lathe with my invention applied thereto,

Figure 2 is an end elevation with the gear case cover removed partly in section,

Figure 3 is a front elevation of the speed changing mechanism,

40 Figure 4 is a sectional view of part of the mechanism shown in Fig. 3, and

Figure 5 is a top view to Figure 3.

Referring to the drawings in which like characters of reference indicate corresponding parts wherever occurring, power is transmitted to the screw machine through a pulley 1 which is connected by a coupling to a drive shaft 2. The latter is journaled in bushings of a gear case 3 and a gear case 45 cover 4. The movement is transmitted from the driving shaft 2 through gears 5, 6 and

7, 8 to a main shaft 9 which drives a main spindle and a threading mechanism. Particular details of these driving connections have not been shown as being immaterial to 55 this invention. From the main shaft 9 movement is also transmitted through spur gears 10 and 11, bevel gears 12 and 13, and a worm drive 14 and 15 to a cam shaft 16. Mounted on this cam shaft are 60 several cams of which 17 is a cam for actuating a turning tool carrier 19 while 18 represents a cam for controlling the movement of a form tool carrier 20.

The driving shaft 2 rotates at a constant 65 fast speed, while the main cam shaft 16 rotates at a slow constant speed, which may be varied by using different gears in accordance with the time required for producing a certain part. An auxiliary cam shaft 21 is 70 mounted rotatably in bearings of the gear case 3 and the cover 4.

To accomplish the desired object, that is to rotate the cams mounted on the auxiliary cam shaft slowly during the cutting operations and very fast during the nonproductive period and yet complete each revolution synchronously with the main cam shaft, two gear 22 and 23 are provided, of which gear 22 is driven by the slowly rotating cam shaft 75 80

16 through a gear 24 while gear 23 is rotated by the fast running drive shaft 2 through a gear 25, and the auxiliary cam shaft 21 is coupled alternately with these two gears 22 and 23. A clutch 26 disposed 85 between the gears 22 and 23 is mounted slid- 90

ingly on but fixed rotatably to shaft 21 by means of a pin 27 which is driven into shaft 21 and extends through slots cut into the clutch. Two notches spaced at 180° are cut

95 into one face of the clutch 26 and two corresponding noses 28 integral with gear 22 fit therein, while clutch teeth 29 have been cut into the opposite face of the clutch member 26 and mate with teeth cut into the hub of the gear 23. The gear 22 is journaled with a hub in the bearing 30 of the gear case 3, collar 31 holding it against axial movement. Similarly the gear 23 is located in the bearing 32 of the cover 4 with a collar 100 33 preventing axial play. Thrust ball bearings are interposed between the gear 23 and

the cover 4 and the gear 23 and a sleeve 34 in order to take up the pressure exerted upon the sleeve 34 by a nose 35 fastened to a lever 36. This lever 36 is pivoted to a hub in the gear case 3 and stands under the influence of a spring 37. Two fork like ends of the lever 36 reach over and under the clutch 26 and carry two rollers 38. These rollers actuated by the spring 37 bear against a rim on clutch 26, when the nose 35 which is fastened to the lower arm of the fork drops into a recess 39 cut into the face of the sleeve 34, and throw the clutch 26 into mesh with the gear 23. The sleeve is fastened by the pin 27 to the auxiliary cam shaft 21 and both rotate in unison with the clutch 26. When rotating further in the direction of the arrow after the nose 35 has dropped into the recess 39 a gradual slope on the backside of this recess pushes the nose 35 and the lever 36 with the rollers 38 back to the original position. A spring 40 disposed around the shaft 21 tends now to throw the clutch 26 out of mesh with the gear 23 and back into engagement with the gear 22 but cannot effect this movement until the notches in the clutch coincide with the two noses 28 on the gear 22, which occurs after a relative movement of 180° between the clutch 26 and the gear 22 has taken place. The spring 37 of course must be considerably stiffer than the spring 40 in order to effect the movements as described.

In order that the auxiliary cam shaft 21 may complete each revolution in the same time as the main cam shaft 16 the gear 22, in case two noses 28 have been provided, must rotate half as fast as the gear 24 or have double the number of teeth. In this case the auxiliary cam shaft 21 rotates approximately half a revolution slow in engagement with the main cam shaft 16 and half a revolution fast in engagement with the drive shaft 2. Actually it moves somewhat more than 180° fast, because the slowly running gear 22 turns a certain distance during the fast movement of the clutch 26. Supposing a different number of noses 28 have been chosen, the ratio between the gears 24 and 22 and between the fast and the slow movement of the shaft 21 must change correspondingly. Two cam plates 41 and 42 for controlling the feeding of the material are formed integral with a cam body 43, while a cam 44 for the radial movement of the cut off tool is secured rigidly thereto. The cam body 43 is mounted on a fluted portion of the auxiliary cam shaft 21 between the bearings 30 and 45 of the gear case 3. A slide 46 is moved upwards by the cam 41 and downwards by the cam 42, rollers 47 and 48 being interposed.

A reciprocating movement of the feed mechanism at right angles to the movement of the slide 46 is caused by an angular ad-

justable guide 49 of U-shaped form, a roller of the feed mechanism fitting into this recess and transmitting the movement.

The cams for controlling the various operations are divided into two groups of 70 which the one comprises the cams working continuously, for instance cutting off and feeding of the bar of material and the other contains those cams, which are provided for intermittent operations as turning, threading, forming and removing the completed part to a slotting saw or a container. Of course this grouping of the different cams may be varied according to the objects in view. By arranging all the cams 80 working only intermittently on a cam shaft rotating with a constant slow speed it becomes possible to mount the few remaining parts on an auxiliary cam shaft, which may turn slowly during the cutting period and 85 may be accelerated during the noncutting time at a much faster rate than would be possible otherwise. In the machines actually built and successfully operated the time consumed for the fast operation of the auxiliary cam shaft is one sixth of a second and 90 yet the blow when engaging the auxiliary cam shaft with the fast rotating shaft is hardly perceptible.

Having now fully explained my invention 95 I do not wish to be understood as limiting myself to the exact details of construction as obviously many modifications will occur to a person skilled in the art.

What I claim is:

1. In combination a shaft rotating at a constant slow speed, a member rotating at a constant fast speed, a second rotating member in engagement during each revolution alternately with said slow speed shaft and 105 said fast rotating member and controlling means for causing said second rotating member to complete each revolution in the same time as said slow speed shaft.

2. In combination a shaft, a member rotating in fixed relation to said shaft, engaging means on said member, a different member rotating at a fast speed also carrying engaging means a rotating part engaging alternately with said two members and controlling means for causing said rotating part 115 to complete each revolution in the same time as said shaft.

3. In combination a shaft carrying cams, a part turning in fixed relation to said cam 120 shaft, a drive shaft, a different part driven in fixed relation by said drive shaft, both parts carrying engaging means, another shaft also carrying cams and a coupling mounted on said latter cam shaft for 125 engaging with both said parts and means for effecting alternate engagements.

4. In turning and screw cutting machines a cam shaft, a gear rotating in relation to said cam shaft and carrying two engaging 130

- means, a member rotating at a fast speed also carrying engaging means, an auxiliary cam shaft carrying two engaging means mating with the engaging means on said gear and other engaging means to couple with the engaging means carried by the member rotating at a fast speed, and separate means for alternately effecting engagement with both said engaging means.
- 10 5. In turning and screw cutting machines a cam shaft, a gear driven by and rotating at half the speed of said cam shaft and carrying two engaging means, another gear rotating at a fast speed carrying different engaging means, an auxiliary cam shaft, a coupling member rotating with but sliding on said auxiliary cam shaft to engage alternately with said two gears and means for effecting this alternate engagement.
- 15 6. In turning and screw cutting machines a drive shaft, a main cam shaft, an auxiliary cam shaft, a coupling member driving said auxiliary cam shaft and rotating alternately in fixed relation to said main cam shaft and said drive shaft and means rotating with said auxiliary cam shaft for controlling the alternate engagement of said coupling member.
- 20 7. In turning and screw cutting machines a cam shaft, a drive shaft, an auxiliary cam shaft, a coupling member driving said auxiliary cam shaft and being driven alternately during each revolution by said cam shaft, a cam for controlling these alternate engagements rotating with said auxiliary cam shaft and springs for effecting these alternate couplings.
- 25 8. In turning and screw cutting machines a cam shaft, a driving shaft, an auxiliary cam shaft, being alternately driven by said cam shaft and driving shaft and completing each revolution in the same time as the main cam shaft and cams turning with the auxiliary cam shaft for controlling the feed of the material through the machine.
- 30 9. In turning and screw cutting machines a cam shaft, a driving shaft, an auxiliary cam shaft, being alternately driven by said cam shaft and said driving shaft and completing each revolution in the same time as the main cam shaft, a plurality of cams mounted on the auxiliary cam shaft and another plurality of cams mounted on and turning with the cam shaft, said cams controlling the various operations necessary to complete a part.
- 35 10. In turning and screw cutting machines a main cam shaft, a driving shaft, an auxiliary cam shaft being alternately driven by said cam shaft and said drive shaft and completing each revolution in the same period of time as the main cam shaft, cams for controlling the feeding movement of the material and the cut off operation being mounted on said auxiliary cam shaft and other cams mounted on and turning with said main cam shaft for controlling different operations necessary for completing a part.
- 40 11. In turning and screw cutting machines a plurality of cams rotating at a uniform speed and making one revolution for each part completed and other cams rotating alternately during each revolution at a slower and a faster speed than the first cams and completing also each revolution in the same time as said first cams.
- 45 12. In turning and screw cutting machines a plurality of cams rotating at a uniform speed, other cams rotating alternately faster and slower than the first cams and completing each revolution in the same time as taken by the first cams for one revolution, a feeding mechanism and cut off means, both feeding mechanism and cut off means being controlled by the latter cams rotating at a variable speed.

In testimony whereof I affix my signature.

LORENZ KONRAD BRAREN.
